United States Patent Office

Des. 221,897

Patented Sept. 14, 1971

221,897

BOTTLE DISPENSER

Louis Brodsky, Parlin, N.J., assignor to E. R. Squibb & Sons, Inc., New York, N.Y.

Filed May 7, 1970, Ser. No. 22,880

Term of patent 14 years

Int. Cl. D20—01

U.S. Cl. D52—2

FIG. 1

FIG. 2

FIG. 1 is a front elevation of a bottle dispenser showing my new design; and

FIG. 2 is a top plan view.

The side opposite FIG. 1 is substantially similar thereto. The bottom is substantially plain and unornamented.

I claim:

The ornamental design for a bottle dispenser, as shown and described.
